ANTENNA ROTATOR

Edward L. Barrett, La Grange, Ill.

Application August 22, 1951, Serial No. 243,108

9 Claims. (Cl. 310—67)

1

This invention relates to remotely controllable rotators for adjusting the rotary position of directional antennas. Such rotators are widely used in connection with the reception of television and other high frequency radio signals, in order that signals from any desired direction may be received with maximum efficiency.

An object of the invention is to provide an antenna rotator which may be coaxially disposed on its stationary supporting mast, or the like, and which carries the antenna in a coaxial relationship with the mast. As a result of this arrangement, the rotator imposes only an end thrust on the mast, without imposing any bending stress. Moreover, the rotator presents an unusually pleasing functional appearance.

A further object is to provide a rotator in which the working parts are enclosed in a circular housing which rotates with the antenna, the housing being rotatably supported on a stationary central member which extends upwardly into the housing. It is a related object to provide unusually effective sealing means to exclude dust and water from the working parts, the sealing means being interposed between the housing and the stationary supporting member.

A further object is to provide an antenna rotator which is unusually sturdy and dependable, but nevertheless inexpensive and relatively easy to manufacture.

Further objects, advantages, and features of the invention will appear from the following description of an illustrative embodiment, the description being taken with the drawings, in which:

Figure 1 is a perspective view of an antenna installation including an antenna rotator embodying the features of the invention;

Fig. 2 is a perspective view on a larger scale of the antenna rotator;

Fig. 3 is a perspective view of the rotator, partly in axial section to illustrate details of the driving mechanism for producing antenna rotation;

Fig. 4 is a horizontal sectional view of the upper portion of the rotator, taken along a line 4—4 of Fig. 3;

Fig. 5 is a horizontal sectional view taken through the lower portion of the rotator along the line 5—5 of Fig. 7, illustrating a rotatable signal-carrying connection;

Fig. 6 is a fragmentary axial section taken along the line 6—6 of Fig. 5; and

Fig. 7 is a fragmentary axial section taken along the line 7—7 of Fig. 5.

2

While the invention is susceptible of various modifications and alternative constructions, there is shown in the drawings and will herein be described in detail the preferred embodiment, but it is to be understood, however, that there is no intention to limit the invention to the form disclosed, but it is intended to cover all modifications and alternative constructions falling within the spirit and scope of the invention as expressed in the appended claims.

Referring now to Fig. 1 of the drawings, the antenna installation includes a conventional television antenna 18 suitably mounted upon a rotatable antenna mast section 12. A fixed mast section 14 is disposed in coaxial alignment with the rotatable mast section 12, and the two sections are coupled together for rotation of the section 12 with respect to the section 14 by means of an antenna rotator 15 including a housing 16 in which is disposed all of the control elements and instrumentalities provided to effect rotation of the antenna under the control of a remotely located control station. The means for remotely controlling the orientation of the antenna is fully described and specifically claimed in my copending application entitled "Directional Control Mechanism for Antennas," Serial No. 230,266, filed June 7, 1951, to which reference may be had to supplement the brief description contained in this application.

The housing 16 has a closed upper wall 17 provided with a coaxially disposed, upwardly projecting post 18 (Fig. 3) which is adapted to be inserted into the lower end of the rotatable mast section 12. In order to accommodate masts of various internal diameters, the post 18 is provided with a split upwardly tapering conical bushing 20 therearound having an axial bore therein for reception of the post. It will be apparent that masts of relatively small internal diameters will engage the bushing 20 adjacent the upper region thereof, while masts of larger internal diameters will move further downwardly on the bushing.

The rotatable mast section 12 is mounted in coaxial relationship on the housing 16 by means of a supporting structure which is fully described and specifically claimed in my copending application Serial No. 230,268, filed June 7, 1951, and entitled "Antenna Mast Clamp," to which reference may be had to supplement the following brief description. The supporting structure includes an expandable and contractible clamping band 21 (Fig. 2) adapted to engage the mast section 12 at a region spaced upwardly above the

housing 16 and a similar contractible band 22 adapted to engage the housing 16. A series of struts or supports 24 serves to connect the two bands 21 and 22 and maintain the rotatable mast structure or section 12 upright.

The housing 16 is formed in two sections including an upper bell-shaped section 26 and a lower generally tubular section 28, the two sections being suitably secured together as by means of attachment screws 30.

The upper end of the non-rotatable mast section 14 is adapted to be received within a clamping mechanism 32, which is fully described and specifically claimed in the previously mentioned copending application, entitled "Antenna Mast Clamp," Serial No. 230,268, filed June 7, 1951. Briefly, the clamping mechanism 32 includes an inverted socket member 33 to which there is secured a plurality of axially extending clamping arms 34. Sectional clamping bands 36 which are in turn secured to the arms 34 include screws for applying peripheral gripping pressure to the upper end of the mast section.

The clamping mechanism 32 supports a stationary cage or framework 35 (Fig. 3) upon which there is supported an electrical driving motor M for rotating the antenna 10. In accordance with a feature of the invention, rotation of the antenna is obtained by rotating the housing 16 to which the antenna mast section 12 is fixedly secured. The framework 35 is supported in turn by a U-shaped lower bracket 36 having arms 36a and 36b which straddle the framework and which are fastened thereto by screws or the like (see Fig. 4). The bracket 36 is fixedly mounted on the mast-receiving socket member 33 by means of a post or pillar 37 (Fig. 7), which has upper and lower threaded shanks 38 and 39 extending through apertures 40 and 41 in the bracket and the socket member respectively. The bracket and the socket member are clamped between upper and lower shoulders 42 and 43 on the pillar and upper and lower nuts 44 and 45 threaded on the shanks 38 and 39.

The cage or framework 35 (Fig. 3) is provided with a top wall 46 to which there is secured an inverted U-shaped bracket 47 (Figs. 3 and 4). The motor M is provided with a motor shaft 48 on which there is mounted a gear pinion 49 (Figs. 3 and 4) which meshes with a larger gear 50 mounted on a shaft 52 journaled between the top wall 46 of the cage and the bracket 47. A pinion 54, which may be integrally formed with the gear 50, meshes with a larger gear 56 carried on a shaft 58 likewise journaled between the top wall 46 of the cage 35 and the bracket 47. A pinion 60, which may be integrally formed with a gear 56, meshes with a gear 62 mounted on a shaft 64 rotatably journaled between the top wall 46 of the cage 35 and the upper portion of a second inverted U-shaped bracket 66 suitably secured to the cage 41. A gear 68 is secured to the shaft 64 and is in constant mesh with a ring gear 70 which is centrally disposed within the upper casing section 26 and is secured in position by means of a series of radially spaced anchoring bolts 72. The ring gear 70 is recessed centrally to provide a socket 71 therein for reception of a ball thrust bearing 73 rotatively mounted on a post 75 carried on the bracket 47. The bearing 73 absorbs substantially all of the downward vertical thrust of the antenna installation. From the above description of parts, it will be seen upon energization of the motor M and consequent rotation of the motor shaft 48 a direct drive will

exist through the train of gears including the gears 49, 50, 54, 60, 62, 68 and 70 to the housing 16 on which the rotatable mast section 12 is mounted.

5 The lower section 28 of the housing 16 is provided with a generally cylindrical well portion 80 having an inwardly directed flange 82 (Fig. 7) at its lower end. A resilient sealing ring or gasket 84 is interposed between the housing and the stationary axial clamping or supporting means 32, in order to form a rotary seal to exclude dirt and moisture from the rotatable housing 16. In this instance the gasket fits snugly between the outer surface of the socket member 33 and the inner surface of the housing well 80. The gasket has a groove 86 to receive the inner edge of the flange 82. A stationary sealing plate 88 abuts against the upper surface of the gasket, the plate 88 being clamped between the socket member 33 and the shoulder 43 on the pillar 37. Thus the gasket is confined between the plate 88 and the flange 82. The clamping arms 34, socket member 33, sealing plate 88 and the sealing gasket 84 are non-rotatable, but the well portion 80 rotates with the housing 16 and the antenna 10.

A transmission line or lead-in cable 90 is connected at its upper end to the antenna 10. The transmission line 90 is connected to a lower line section 92 by rotatable connecting means 94 (Fig. 7) positioned in the rotator housing 15. The rotatable connecting means enables the antenna to be continuously rotated in one direction. The rotatable connecting means is fully described and specifically claimed in my copending application, Serial No. 230,267, filed June 7, 1951, and entitled "Lead-in System for Rotatable Antennas." Reference may be made to this copending application to supplement the following brief description. The rotatable connecting means 94 includes two stationary insulated slip rings 96 and 98 fixedly supported along the pillar 37. The slip rings are electrically connected to the lower transmission line section 92. The lower end of the upper transmission line section 90 is connected to a pair of rotatable brushes 100 and 102 which engage the respective slip rings. The lower line section 92 extends from the slip rings through a slot or passage 104 in the sealing gasket 84. The upper line section 90 passes into the housing 16 through an insulating terminal block or bushing 106 which supports the brushes 100 and 102, the terminal block being securely positioned in an opening 108 in the well portion 80 of the housing 16.

55 A control cable 110 (Fig. 7) is connected at its upper end to the motor M and the other instrumentalities for controlling the orientation of the antenna. This control cable not only supplies current to the motor but also carries impulses from a pulsing switch C1, as more completely described in my previously mentioned application Serial No. 230,266. The cable passes downwardly between the pillar 37 and the slip rings 96 and 98, and thence out of the housing 16 through an aperture 112 in the gasket-supporting plate 88 and a passage or slot 114 in the gasket 84. The lower end of the control cable is connected to a terminal block 116 which is mounted on one of the clamping arms 34. A control cable extension 118 extends from the terminal block 116 to the control station (not shown).

Although the operation of the rotator will be apparent from the preceding description, the operation will be briefly summarized. The an-

tenna 10 is rotated by energizing the motor M. The energization of the motor may be controlled from a remote control station (not shown) by means of the control cable 110, 118 in a manner which is fully described in the previously mentioned copending application Serial No. 230,266. By means of the intermediate gears 50, 54, 56, 60, 62, and 68, the rotation of the motor pinion 49 produces rotation of the ring gear 70 secured to the top wall 47 of the housing 16. The housing thereby is rotated on the thrust bearing 73. The rotation of the housing produces rotation of the upper antenna mast section 12 in coaxial relationship with the lower mast clamp 32, the latter providing a stationary support for the motor and the driving gears.

The ring-shaped gasket 84 and the gasket-supporting plate 88 remain stationary along with the socket member 33, but the lower well portion 80 rotates along with the housing 16 so that the inner surface of the well portion slides over the outer surface of the gasket 84. The inwardly directed flange 82 at the downwardly directed mouth of the housing rotates in its retaining groove 66 in the gasket.

As stated, the downwardly directed thrust of the antenna 10 and the upper mast section 12 is carried by the thrust bearing 73 so that the gasket 84 is relieved of any substantial thrust. However, the gasket and the gasket-supporting plate 88 provide a certain amount of lateral support tending to maintain the coaxial alignment of the upper and lower mast sections 12 and 14.

It is to be noted that the gasket is protected by reason of its position and arrangement against the entrance of dirt and moisture and the collection of ice and sleet.

Any ice which does form on the gasket 84 does not impair the operation of the rotator because the resilient gasket is flexed slightly under the driving torque provided by the motor M, and the ice is thereby cracked off the gasket.

As the housing 16 rotates, the rotatable brushes 100 and 102 slide along the stationary slip rings 96 and 98. Thus, the slip rings and the brushes provide a rotatable signal-carrying connection between the upper and lower transmission line sections 90 and 92. By virtue of the rotatable connection, it is possible to rotate the antenna continuously in one direction.

Assembly and servicing of the rotator are greatly simplified by the provision of the separable upper and lower housing sections 26 and 28. This construction permits the mouth of the housing to be narrow so that an effective rotatable seal may be easily and inexpensively provided.

In the event service becomes necessary, the upper portion 26 of the housing may be freed by unscrewing the screws 39 and then sliding such portion axially (upward). To facilitate this, one of the bearing rolls, or both, may have a sliding fit. The gear 70 on the housing will be disengaged from the driving train and the entire mechanism is exposed for inspection and service. If desired, the entire framework which mounts the motor and gear train may be easily detached from the bracket 36 and replaced with a similar drive unit.

Since the entire housing 16 rotates about the stationary axial mast clamp or supporting member 32, the housing is inherently maintained in coaxial relationship with the supporting member. Because the entire housing is rotated, the

rotatable sealing means is unusually effective for excluding dust and moisture.

5 A simple and inexpensive mechanical construction results from mounting the motor M and the drive gears on the stationary support 35 inside the housing.

The present application is a continuation-in-part of my copending applications Serial Nos. 230,266, 230,267 and 230,268, filed on June 7, 1951.

I claim as my invention:

1. In an antenna rotator, the combination comprising a stationary base; means at the underside of said base for supporting the same; a driving mechanism on said base having a frame, driving motor, and gear train terminating in a drive pinion; an inverted bell-shaped housing telescoped over said drive mechanism; a thrust bearing on said frame in coaxial relationship with said housing for engaging the interior wall thereof for supporting the housing and permitting rotation thereof; means mounted on top of said housing in coaxial relationship therewith for supporting an antenna; and a housing gear coaxially fixed in said housing, said drive pinion being positioned for meshing with said housing gear upon said housing being telescoped over said driving mechanism and into seated position on said thrust bearing.

2. In an antenna rotator, the combination comprising a stationary base; supporting means at the underside of said base for coaxial attachment to a supporting pole; a driving mechanism on said base having a frame, driving motor, and gear train terminating in a driving element; an inverted bell-shaped housing telescoped over said driving mechanism; a thrust bearing on said frame in coaxial relationship with said housing and with said supporting means for engaging the interior wall of said housing for supporting the housing and permitting rotation thereof about an axis which is coaxial with respect to the supporting pole; and a driven element fixed to said housing for engaging said driving element in axially disengageable relation thereto for rotation of the housing by said motor; means on the top of said housing in coaxial relationship therewith for supporting an antenna; and a bottom cover peripherally joined to the lower edge of the housing and having a rotatable sealing engagement with said base for sealing the housing against the entry of moisture, said housing having a wide mouth and having a disengageable connection with said bottom cover so that the housing may be axially removed to expose the driving mechanism for service.

3. In an antenna rotator, the combination comprising a stationary base; supporting means at the underside of said base for coaxial attachment to a supporting pole; a driving mechanism on said base having a frame, driving motor, and gear train terminating in a driving element; an inverted bell-shaped housing telescoped over said driving mechanism; a thrust bearing on said frame in coaxial relationship with said housing and with said supporting means for engaging the interior wall of said housing for supporting the housing and permitting rotation thereof about an axis which is coaxial with respect to the supporting pole, and a driven element fixed to said housing for engaging said driving element in axially disengageable relation thereto for rotation of the housing by said motor; means on the top of said housing for supporting an antenna coaxially with respect thereto; said housing having a bottom cover in the shape of an annular

flange with outer and inner edges, the outer edge of said flange having a disengageable sealing connection with said housing; and an annular sealing member of rubber or the like between the bottom cover and said base, said sealing member having a diameter which is considerably less than said housing for the production of high break-away force at the sealing surfaces.

4. In an antenna rotator for rotating an upper antenna-carrying mast relative to a stationary mast, the combination comprising a stationary base, a clamp on the underside of said base for coaxial attachment to the lower mast, a driving mechanism on said base and including a frame and a driving motor, a 15 thrust bearing mounted on said frame in coaxial relationship with said clamp, a bell-shaped housing telescoped over said driving mechanism and seated coaxially on said bearing for rotation thereon in coaxial relationship with the lower mast, means connecting said driving motor to said housing for rotating the latter, and a clamp mounted on top of said housing in coaxial relationship therewith for supporting the upper mast coaxially relative to the lower mast.

5. In an antenna rotator for rotating an antenna relative to a stationary mast, the combination comprising a stationary base, supporting means on the underside of said base for coaxial attachment to the mast, a driving mechanism on said base and including a frame and a driving motor, a thrust bearing mounted on said frame in coaxial relationship with said supporting means, a bell-shaped housing telescoped over said driving mechanism and seated coaxially on said bearing for rotation thereon in coaxial relationship with the mast, means connecting said driving motor to said housing for rotating the latter, and means mounted on top of said housing in coaxial relationship therewith for supporting the antenna.

6. In an antenna rotator for rotating an antenna-carrying mast, the combination comprising a stationary base, means at the underside of said base for supporting the same, a driving mechanism on said base and including a frame and a driving motor, a thrust bearing mounted on said frame, a bell-shaped housing telescoped over said driving mechanism and rotatably carried on said bearing in coaxial relationship therewith, means connecting said motor to said housing for rotating the latter, and a clamp mounted on top of said housing in coaxial relationship therewith for supporting the antenna-carrying mast.

7. In an antenna rotator, the combination comprising a stationary base, means at the underside of said base for supporting the same, a driving mechanism on said base and including a frame and a driving motor, a thrust bearing mounted on said frame, a bell-shaped housing telescoped over said driving mechanism and rotatably carried on said bearing in coaxial relationship therewith, means connecting said motor to said housing for rotating the latter, and means mounted on top of said housing in coaxial relationship therewith for supporting the antenna.

8. In an antenna rotator for rotating an upper antenna-carrying mast relative to a stationary mast, the combination comprising a stationary cylindrical base, a clamp on the underside of said base for attaching the base coaxially to the lower mast, a driving mechanism on said base

including a frame and a driving motor, a thrust bearing mounted on said frame in coaxial relationship with said base, a bell-shaped housing telescoped over said driving mechanism and seated coaxially on said bearing for rotation thereon in coaxial relationship with the lower mast, means connecting said driving motor to said housing for rotating the latter, a clamp mounted on top of said housing in coaxial relationship therewith for supporting the upper mast coaxially relative to said lower mast, said housing having an annular bottom cover with outer and inner edges, the outer edge of said cover having a disengageable sealing connection with said housing, the inner edge of said cover being disposed coaxially around said cylindrical base, a retaining flange mounted on said base and spaced above the inner edge of said cover, and an annular sealing member of rubber or the like having a portion disposed between the inner edge of said cover and said base for supporting said housing against lateral displacement relative to said base, said annular member having an outwardly extending flanged portion at its upper end disposed between said cover and said retaining flange for retaining the housing on said thrust bearing against upward movement relative thereto.

9. In an antenna rotator for rotating an antenna relative to a stationary mast, the combination comprising a stationary cylindrical base, means on the underside of said base for attaching said base coaxially to the mast, a driving mechanism on said base including a frame and a driving motor, a thrust bearing mounted on top of said frame in coaxial relationship with said base, a gear coaxially seated on said thrust bearing, a bell-shaped housing telescoped over said driving mechanism and fixed coaxially to the top of said gear, said driving mechanism having a gear train connected between said driving motor and said gear for rotating said housing coaxially relative to the mast, means mounted on top of said housing in coaxial relationship therewith for supporting the antenna, an annular bottom cover having outer and inner edges, the outer edge of said cover having a disengageable sealing connection with said housing, the inner edge of said cover being disposed coaxially around said cylindrical base, a retaining flange on said base and spaced above the inner edge of said cover, and an annular sealing member of rubber or the like having a portion disposed between the inner edge of said cover and said base for supporting said housing against lateral displacement relative to said base, said annular member having an outwardly extending flanged portion at its upper end disposed between said cover and said retaining flange for retaining the housing against upward movement and thereby maintaining the gear in seated relationship with said thrust bearing.

EDWARD L. BARRETT.
